UNITED STATES PATENT OFFICE.

OTTO J. GROEHN, OF DETROIT, MICHIGAN, ASSIGNOR TO CLAYTON & LAMBERT MFG. CO., OF DETROIT, MICHIGAN, A CORPORATION OF MICHIGAN.

FIRE-POT CONSTRUCTION.

Application filed May 19, 1923. Serial No. 640,191.

This invention relates to fire pots and refers more particularly to what is known as coil fire pots, that is, in which a preheating coil or the like is mounted on the supply tank 5 and the products of combustion from the burner utilized for heating this coil as well as heating the tool or other article to be heated. Among the objects of the invention are; to provide an improved manner of mounting the 10 various parts on the tank and in the novel arrangement whereby the parts are readily removable for renewal, repair or any other desired purpose. One particular object of the invention is the provision of a shield for the 15 burner and coil which can be formed of sheet metal stampings or the like and be readily removed without disconnecting the burner and coil from the tank. Other features of the invention reside in the novel arrangement of 20 the spider or plate which connects the tank with the various parts mounted thereon; in the novel construction of filler plug and in such further features of construction and arrangements and combinations of parts as will 25 more fully hereinafter appear.

In the drawings:

Figure 1 is a side elevational view partly in section through a tank embodying my invention;

30 Figure 2 is a top plan view of the parts shown in Figure 1, partly broken away;

Figure 3 is a section on the line 3—3 of Figure 1, showing only the shield;

Figure 4 is a detail plan view of the spider 35 which is connected to the top of the tank;

Figure 5 is a section on the line 5—5 of Figure 4.

Describing now in detail the particular embodiment of my invention shown in the drawings, A designates the tank of the fire pot, which tank is provided with a filler plug A' and a pressure pump A², the pump being arranged so as to create a pressure in the tank A and through the supply pipe B to the preheating coil C and the burner D whenever the valve B' is opened. The burner D is provided with one or more burner apertures D'. The tank A is generally provided with suitable hydrocarbon or other liquid fuel which is forced, 50 in the manner above mentioned, through the preheating coil to the burner D where it is ignited and the products of combustion are utilized for heating the tool in the holder E or other suitable member mounted on the top 55 plate E².

This top plate E² is mounted on the tank in the following manner; upon the upper end of the tank there is provided a spider or plate F which has three upwardly-offset and outwardly-extending arms F' which register 60 with arms E' on the plate E². This spider or plate may be secured to the tank in any suitable manner such as by soldering or welding and preferably is so secured in a depression A² formed in the upper surface of the tank as 65 shown in Figure 1 of the drawings. Suitable spacer members G and connecting rods G' are provided, each of the latter having its opposite ends extending through apertures F³ and E³ in the spider and plate respectively so that 70 when the parts are assembled and the nuts G² are tightened up on the connecting rods G', the plate E² is secured in fixed relation to the spider F and the tank A. It will be noticed 75 that the spider-shaped plate F, as shown in Figure 4, has a plurality of cut-out portions F² and upwardly projecting lug portions F⁴ which tend to reduce the heat conducted to the tank from the burner and its surrounding shield. 80

Surrounding the burner D and the coil C is a shield H comprising an upper frustoconical portion which fits into a groove I in the plate E² and a lower cup portion J which fits over the spider F. The cup portion J 85 has its bottom upwardly offset as at J' so as to form a recess J² which will fit over the lugs F⁴ on the spider F. Thus the cup portion J is provided with a downwardly opening recess or cup-shaped portion which fits over 90 the lugs on the spider F and an upwardly opening recess or cup-shaped portion which receives the lower end of the upper portion of the shield H. This latter is preferably formed in two or more sections so constructed 95 and arranged that they can be removed without in any way affecting the burner D or the preheating coil C. The latter is connected through suitable piping K and connections K² to the tank and in removing the shield H 100 it is not necessary to affect the piping and connections or the burner.

In detail the upper portion of the shield H is formed in two sections L and L'. (See Fig. 3). One side of each of these sections is 105 adapted to fit into a recess M in the edge of the other section and the parts are so constructed and proportioned that when assembled the two sections L and L' will be interlocked and their lower ends received tightly 110

within the upwardly-opening recess or cup-shaped portion of the cup J while their upper ends are locked in the recess I in the plate E. As is best seen in Fig. 1, the pipe K' supplying fuel to the coil C passes through an opening H' in the shield H, formed at the junction of the sections L and L' of said shield, thus avoiding interference by said pipe with removal of the hood. After the parts are assembled in this position, the spider F and connecting rods G' are inserted in position and the nuts G² tightened up so as to lock the parts rigidly in their assembled position. When, however, it is desired to remove either 15 of these sections for the purpose of repair or renewal it is only necessary to unfasten the nuts G² and lift the cover plate and connecting rods upwardly which will release the upper end of the sections L and L' and allow 20 them to be drawn upwardly out of engagement with the cup J and then separated. Moreover, this is accomplished without affecting the position of either the burner or the coil and permits replacements to be quickly 25 and conveniently made. Moreover, by this novel arrangement the top plate is carried by a single connection to the tank which avoids the necessity of soldering or otherwise securing a plurality of uprights to the tank as has 30 been previously done. As the plate E² is provided with ears or lugs N which form the handle connections, the tank containing the liquid fuel is in reality carried by the top

plate whenever the fire pot is carried by the handle and the connection between the top 35 plate and the tank is through the spider F which is secured to the upper end of the tank as a unit.

The filler plug A' is also formed in a novel manner, this filler plug having a handle portion O and a lower threaded portion Q which is connected to the handle by a shank portion Q' which has an outwardly-extending flange R into which is secured the inwardly bent end S of the metal cap T. This construction has an advantage over previous structures in that it is not only rigid but that it can be economically formed and readily attached and detached as a unit.

What I claim as my invention is:

In a fire pot or the like, a tank, a burner mounted on the tank, a shield surrounding the burner, said shield comprising a plurality of detachable sections, a spider having face contact with the tank, a plate, a pipe for supplying fuel from said tank to said burner, said pipe projecting through said shield, and clamping means between said spider and plate for holding the sections of the shield in assembled condition therebetween, and means 55 permitting removal of the shield sections upon removal of the plate without disturbing the remaining said elements of the fire pot.

In testimony whereof I affix my signature.
OTTO J. GROEHN.
